UNITED STATES PATENT OFFICE.

CYPRIAN U. CRANDALL, OF STERLING, ILLINOIS.

CORN-PLANTER.

SPECIFICATION forming part of Letters Patent No. 252,194, dated January 10, 1882.

Application filed May 18, 1881. (Model.)

To all whom it may concern:

Be it known that I, CYPRIAN U. CRANDALL, a citizen of the United States, residing at Sterling, in the county of Whitesides and State 5 of Illinois, have invented certain new and useful Improvements in Corn-Planters; and I do hereby declare the following to be a full, clear, and exact description of the invention, such as will enable others skilled in the art to which 10 it appertains to make and use the same, reference being had to the accompanying drawings, and to letters or figures of reference marked thereon, which form a part of this specification.

15 My invention relates to improvements in seed-planters in which perforated, rotating, and laterally-moving seed-plates are operated by being geared to the ground-wheel, and in which the seed-boxes are placed upon the rear 20 frame of the machine.

The objects of my invention are, first, to regulate more closely the number of seeds to be planted in one hill; second, to furnish a machine in which the operator of the dropping 25 devices may be seen by the operator, thus enabling him to drop with greater accuracy, and also to see that the devices are doing their work. I attain these objects by means of the mechanism illustrated in the accompanying 30 drawings, in which—

Figure 1 is a plan view, showing in a general way the construction of the machine. Fig. 2 is a side elevation of the machine. Fig. 3 is a rear elevation of the front frame of the machine, 35 showing the mode of operating the second drop. Fig. 4 is a rear elevation of the seed-boxes and a portion of their attachments, showing the transverse shaft, bevel-gearings, and a portion of the self-adjusting shaft which connects the 40 seed-plate with said bevel-gear. Fig. 5 shows the flutter-valve or second drop. Fig. 6 is a vertical section of the boot or heel of the runner, showing the position of the second drop. Fig. 7 is a plan view of the bottom of the seed- 45 box, showing the seed or drop plate with preliminary and final cut-offs. Fig. 8 is a view of the under side of the seed or drop plate and the top plate with its lugs arranged around the seed-plate. Fig. 9 is a front view of the 50 final cut-off, with the cover removed to show the sliding bars and the spring at the up-

per end of such bars. Fig. 10 is a front view and a section of the cover for the sliding bars in the final cut-off. Fig. 11 is a sectional view of the final cut-off through the line $\alpha\alpha$ in Fig. 55 7. Fig. 12 is a vertical section of the lower part of the seed box, the seed-tube, and the boot of the runner.

Similar letters refer to similar parts throughout the several views.

The body of my machine consists of the two frames A and A', Figs. 1 and 2. The frame A is supported by the ground-wheels B B, while the frame A' is supported by the runners C C and the governing-wheels D D. The two 60 frames are united by the common hinge N and the swivel-hinge X, Figs. 1 and 2. The hinge N allows the frame A' to bend downward or upward to adjust the runners C C to the undulations in the ground when such undulations extend from side to side of the planter. The swivel-hinge X allows the frame A' to rotate upon its axis, so as to raise or lower but one 65 side of the frame A' when the runner on one side meets an elevation or depression which is not met on the other side.

Beneath the frame A' are set rigidly the bars g g, extending backward toward the seat of the driver. To such ends is attached by a hinge the rack U, which rack is forced upward or downward by means of the pinion V and the foot-cranks v v. The driver may by means of this mechanism raise or lower the frame A' at will. The ends of the slide-bar w may be set between the cogs of the pinion V, 70 thus locking the pinion and setting the runners C C rigidly at any desired depth. This also forms a means of raising the frame A' 75 permanently out of the ground for turning or driving when not planting.

Unlike other machines which have come under my observation, my machine has the seed-boxes and most of the dropping devices placed upon the rear frame, A, only the second drop being attached to the front frame, A'. My object in using this arrangement is to fix the gearing which operates the dropping devices rigidly, so that it may work with greater perfection than would be the case were a part of the gearing seated upon the front frame, A'. 95

E is a bevel driving-gear attached to the hub of the ground or covering wheel B, and turns 100

the drive-shaft F, which is provided with the bevel-gear a, which latter gear a meshes into the bevel-gear b on the transverse shaft G. This shaft G is provided with the bevel-gears c c, which operate the gears d d, Figs. 4 and 12. The gears d d are connected with the under side of seed-plate I I by means of the self-adjusting shaft H, which is joined loosely at its ends by means of four-sided sockets to such 10 gears d d and seed-plates I I, as shown in Fig. 12. When the gearing, as described, is operated by the motion of the ground-wheel B the seed-plate I is revolved or rotated. The seed-plate I is placed against the under side of the 15 top plate, J, and on the under side of such plate J, and around the seed-plate I, are placed the lugs f f f f f f. When the drop-plate I is rotated its rounded corners strike the lugs f f f f f f, thus pushing such plate irregularly from 20 side to side. It will be observed, Fig. 8, that I place one corner less on plate I than there are lugs f f, &c. This is essential to produce the irregular motion mentioned. When one lug f is met by a corner of the plate the lug opposite 25 is between two corners, thus giving the plate room to slide in the direction of the last-named lug to allow the opposite corner to slide by the lug which it has met. Plate I is provided with the seed-holes h h h, &c., Fig. 7. The jarring 30 and the irregular motion of the plate I while it rotates agitates the corn continually, thus preventing it from bridging over the seed-chambers. The result is that the seed-holes are always promptly filled.

35 In Fig. 7, l l, &c., are yielding preliminary cut-offs, made of wire or other elastic material. When more than one grain attempts to settle into the holes or seed chambers h they cannot settle below the surface of plate I, the seed-chamber being deep enough to receive only one 40 grain below its rim. These preliminary cut-offs l l will then scrape out the grains, so that the chamber may refill properly. When the chamber is once properly filled it passes on 45 with the one grain unmolested by the succeeding preliminary cut-offs, under the final cut-off K, and over the upper end of the tube L, Fig. 12.

Figs. 9, 10, and 11 show in detail the construction of the final cut-off K.

50 O is a box or arch, attached rigidly to the top plate, J, and the wall of such box, which is toward the approaching seed-chamber, is inclined to the seed-plate I, as shown in Fig. 11. The angle of such inclination which I find most 55 advantageous is about forty-five degrees. The outer surface of this wall is provided with grooves, in which rest the sliding bars i i i, Figs. 9 and 11. The bars i i i are each provided with a shoulder or stop, i', to prevent the 60 lower end from bearing upon the seed-plate I, and also to form a bearing for the spring k.

Q is a cap or cover, placed over bars i i i and spring k to hold these bars in place. Should a large grain or more than one grain be in one 65 of the seed-chambers h when coming to the bars i i i, such bars will yield and slide backward and upward sufficiently to allow the corn

in the chamber to pass. The spring k causes the bars i i i to fall again as soon as the chamber has passed. I use several bars i, because 70 by so doing the opening made to admit the corn in the chamber into the cut-off box O will be made just as large as necessary and no larger. When the corn in the chamber comes in contact with the cut-off it does so ordinarily 75 at but one point. By using several bars only the particular bar i which is met by the corn is pressed upward, while the others remain in place, thus preventing the corn outside of the seed hole or chamber from passing through 80 the cut-off, as would be the case if the whole cut-off were raised. The seed hole or chamber, after passing the final cut-off, K, passes to the opening in the lower or bottom plate, R, where the upper end of the tube L is attached. The 85 corn will ordinarily fall of its own weight down such tube L. Sometimes, however, a grain may lodge in the seed-hole in such a manner as not to fall out of its own weight. To remedy this difficulty I place the ball P loosely into 90 the chamber O, Figs. 11 and 12. The motion of the seed-plate I will bring the ball over the seed-chamber h and cause its weight to fall upon the corn in such seed-chamber. The weight of such ball P is certain to discharge 95 the corn from the seed-hole. Tube L conducts the falling corn from the final cut-off into the upper part of the boot M. At or near the bottom of such boot M is fixed transversely the fan-like wheel or flutter-valve S, which forms 100 the second drop. The first drop above described, it will be observed, is operated by means of gearing connecting it with the ground-wheel B. The second drop, on the contrary, is operated by means of the lever or check-rower usually employed in corn-planters. The 105 flutter-valve S has the wings m m m, &c. These form troughs or chambers q q, &c.

110 Into the upper part of the boot M is fixed the vertical transverse partition p, extending down upon the flutter-valve S in such manner as to leave only one chamber q open at a time to receive the corn as it falls from the upper or first drop. From the lower end of the partition p a suitable number of wires extend backward over the flutter-valve S to keep the corn 115 from falling out of the chambers q prematurely. I use wires because they will allow the driver to see the corn as it lies in the chamber q before it is discharged, the wires being placed 120 just near enough together to keep the corn from passing between them. The seed-plate I in operation as above described revolves continually, dropping the corn grain by grain in the stationary chamber q, (the one turned 125 upward.) The gearing operating plate I is so adjusted as to drop the required number of grains into chamber q while the planter moves from one hill to the other.

130 The flutter-valve S is operated by means of a ratchet, T, attached to the end of the axis of such valve, the pawls r r, the gate s, upon which the pawls r r are fastened, the elbows t t, and the vibrating bar n, Figs. 3 and 5. The vi-

brating bar *n* is seated against the frame *A'*, near the hinge joint, and is provided with the usual hand-lever. One movement of the vi-

5 brating bar *n* will revolve the flutter-wheel *S* sufficiently to carry the chamber *q* (which has been uppermost and is filled with corn) backward far enough to bring the next chamber *q* uppermost, so as to allow it to receive the corn as it falls from the seed-plate *I*. The chamber 10 *q* which is filled with corn now rests under the wires *o*, Fig. 12, and at the next movement it is revolved far enough to discharge the corn into the furrow made by the runner *C* and the boot *M*.

15 Some parts of my machine are not new. For that reason I have deemed it unnecessary to describe such parts in detail.

What I claim as my invention, and desire to secure by Letters Patent of the United States, 20 is as follows:

1. The combination of the rear frame, *A*, having the first seed-dropping devices located on the front part thereof and provided with the seed-tubes *L*, and the front frame, *A'*, carrying 25 the runners *C*, provided with the second dropping devices arranged to receive the seed from said seed-tubes and deposit the same in the furrows, substantially as described.

2. The combination, with a seed-box, of a 30 horizontal rotary seed-dropping plate provided with seed-apertures, and devices for giving said plate an irregular lateral to-and-fro motion simultaneous with its movement about its center, substantially as described, and for the purpose set forth.

3. The combination, with the seed-box having the bottom plate, *R*, provided with the seed-passage and a central opening, of the chambered seed-dropping wheel or plate *I*, having 35 lateral projections, the plate *J*, arranged above said seed-dropping-plate, and provided with the lugs *f*, arranged to strike said lateral projections, and devices for giving to said seed-dropping plate an irregular rotary movement, 45 substantially as described.

4. The combination, with the seed-plate *I*, loosely supported, of the shaft *H*, loosely connected with said plate at one end to communicate rotary motion to said plate, the gear-wheel 50 *d*, loosely connected with the lower end of said shaft, and means for giving to said seed-plate

an irregular lateral to-and-fro movement simultaneous with its rotation, substantially as described, and for the purpose set forth.

5. The combination, with the transverse shaft 55 *G*, provided with bevel-gears *c*, the bevel-gears *d*, the vibratory and rotary shafts *H*, connected with said gears at their lower ends, the suitably-supported seed-plates *I*, and the plates *J*, provided with the lugs *f*, arranged to strike 60 the rounded corners of the said seed-plates and communicate an irregular to-and-fro motion to the same, substantially as and for the purpose set forth.

6. The combination, in a seed-box, with the 65 rotary loosely-supported seed-plate having the rounded corners, of the lugs *f*, arranged to strike said corners as the plate rotates and communicate an irregular to-and-fro motion to said plate, substantially as described. 70

7. In a seeding-machine, the combination, with the seed-dropping plate provided with seed-apertures, of the elastic preliminary cut-off *l*, substantially as described.

8. The combination, with the rotary seed-75 plate provided with seed-apertures, substantially as described, and the final or permanent cut-off bars *i*, of the elastic cut-offs *l*, arranged to bear upon the upper side of said seed-plate, over the apertures thereon, essentially as and 80 for the purpose set forth.

9. The combination, in a seeding-machine, with the first seed-dropping devices mounted upon the rear frame, *A*, and means for operating the same, of the second dropping-wheel, *S*, 85 arranged upon the front frame, *A'*, and having the compartments *q* to receive seed from said first dropping devices, and operated by intermittent moving devices, substantially as described. 90

10. The combination, with the second dropping-wheel, provided with compartments substantially as described, of the elastic screen arranged to cover one of said compartments, for the purpose set forth. 95

In testimony whereof I affix my signature in presence of two witnesses.

CYPRIAN U. CRANDALL.
